(57) CLAIM

The ornamental design for a blanket hoodie, as shown and described.

DESCRIPTION

FIG. 1 is a front, right and top perspective view of a blanket hoodie, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the blanket hoodie that form no part of the claimed design.
